UNITED STATES PATENT OFFICE.

JEROME G. BOWER, OF CHICAGO, ILLINOIS, ASSIGNOR TO PRESSED STEEL CAR COMPANY, OF PITTSBURG, PENNSYLVANIA, A CORPORATION OF NEW JERSEY.

CAR CONSTRUCTION.

No. 922,846.

Specification of Letters Patent. Patented May 25, 1909.

Application filed December 4, 1908. Serial No. 465,912.

To all whom it may concern:

Be it known that I, JEROME G. BOWER, a citizen of the United States, and resident of Chicago, Cook county, Illinois, have invented 5 certain new and useful Improvements in Car Construction, of which the following is a full, clear, and exact description, reference being had to the accompanying drawings, in which like reference characters refer to like parts, 10 and in which—

Figure 1 is a sectional plan view of the underside of so much of a car body as is necessary to illustrate my invention; Figs. 2 and 3 are detail views of the car body corner castings; Figs. 4 and 5 are like views of the door corner castings; Figs. 6 and 7 are like views of the center sill and transom brace castings.

An object of the present invention is to reinforce a car body in which the bottom of the 20 car is composed entirely or almost entirely of drop doors, without interfering with the discharging of the car, the opening or closing of the car doors or car attachments.

With this end in view, and referring to the 25 drawings in detail, 1 represents the car center sill structure, 2 the car sides, 3 the car end and 4 transoms or cross-bearers extending between the center sill structure 1 and the sides 2.

30 5 are drop doors hinged in any suitable manner to the car underframe, such, for instance, as shown at 6, Fig. 1. On the underside of each of the doors 5 I rivet or secure a diagonal brace member 7 of suitable section, 35 preferably of Z-section. At each end of this member or, at opposite points, on the corners of the door 5 I rivet or secure door corner braces 8 which abut preferably the ends of the brace member 7 and are provided with 40 angular projecting engaging faces 8^a.

9 are car body corner brace castings provided with angular recessed engaging faces 9^a and riveted or secured to the car body in suitable location, each opposite a door corner 45 brace casting 8. 10 are center sill and transom brace castings having recessed angular engaging faces 10^a and riveted to the car body each opposite a door corner brace casting 8.

50 The location of the several parts as shown in Fig. 1 may be varied by changing the direction of the diagonal brace member 7 so

that they run from the central outer end portion of the car toward the interior portion of the car sides, or in a direction at right angles 55 to the direction shown in Fig. 1, in which event car body brace castings 9 would be suitably mounted on or secured to the end central portion of the car body, opposite brace castings 8 and likewise with the castings 10, which would then be located adjacent the car sides 2 instead of at the center sills.

As shown in the drawings the castings 9 may be riveted or secured to the body in such 65 manner that they assist in tying car side and end sheeting together. Likewise the castings 10 may be utilized to assist in tying the cross-bearers and center sill structure together. Car body brace castings 9 are also 70 preferably located just back of the pushpole pockets.

In operation, busling strains or shocks, due to the use of a pushpole against pocket 11, 75 will be transmitted through casting 9, casting 8, brace member 7 and opposite casting 8, through the casting 10 to the center sill structure 1.

Castings 8, 9 and 10 are so mounted that when the doors are closed a very slight gap 80 exists between the respective pairs of castings, so that the slight deflection of the parts of the car frame, due to the busling strain, brings the several castings into engagement to resist said strain, or so that an excess of 85 deflection of the car parts and excessive permanent set is prevented.

Brace members 7 have a further function of stiffening the doors 5 under ordinary 90 usage, preventing distortion of the door due to jerking of the door-raising chains or mechanism at the time of discharging the lading, and also due sometimes to the door becoming jammed by lading the upper limit 95 of its closing movement.

Having thus described my invention, the following is what I claim as new therein and desire to secure by Letters Patent.

1. In a car, a door, a brace secured to said door and means on the car proper adapted to 100 contact with said brace to transmit strains thereto and therefrom.
2. In a car, a door, and a brace for the car proper partly mounted on said door.

3. In a dump car, a drop door and a Z-section diagonal brace riveted to the underside of said door.
4. In a car, a door, a brace extending across said door and means on the car proper in line with and adjacent said brace to transmit strains thereto and therefrom.
5. In a car, a door, a brace extending across said door and enlarged at its ends and means in line with and adjacent the enlarged ends of said brace to transmit strains thereto and therefrom.
6. In a dump car, a drop door, a brace running across said door in combination with means on the car body to transmit strains to and from said brace.
7. In a dump car, a drop door, a brace extending diagonally across the underside of said door and having enlarged ends and means in line with and adjacent the ends of said brace to transmit strains thereto and therefrom.
8. In a dump car, a drop door, a Z-section brace extending diagonally across the underside of said door and having enlarged ends and means in line with and adjacent the ends of said brace to transmit strains thereto and therefrom.
9. In a dump car, a drop door, a brace extending from one extremity to the other of said door and having engaging castings at each end in combination with engaging castings mounted on the car proper and shaped to receive the castings on said door to transmit strains through said door.
10. In a dump car, a drop door and a brace extending across said door and having castings at each end with angular projecting engaging faces in combination with engaging castings with recessed engaging faces adjacent and in line with said door castings to transmit strains through said door castings.
11. In a dump car, a drop door, a brace extending diagonally across said door on its underside, angular castings secured at each end of said brace, an engaging casting secured to the interior corner of the car behind the pushpole pocket adjacent and in line with one of the castings on said door and a similar casting secured to the car cross-bearer and center sill structure adjacent the other of said castings on the door and in line therewith.
12. In a car, a pair of drop doors at one end of the car, and braces on said doors converging toward each other and the longitudinal center of the car.
- In testimony whereof I affix my signature, in presence of two witnesses.
